YARN FEED MECHANISM FOR KNITTING MACHINES

Michael Zimic, Lake Success, and Anton Miskovsky, Deer Park, N. Y.; said Miskovsky assignor to said Zimic

Application March 26, 1951, Serial No. 217,525

8 Claims. (Cl. 66—127)

1

The present invention relates to means for feeding yarn in knitting machines and, more particularly, to the novel addition of a yarn feeder to the mechanism of a knitting machine without changing or enlarging the machine. The invention also contemplates the provision of novel means for controlling the position of a yarn feeder and its carrying means over a predetermined range of movement to facilitate special knitting operations or special knitting sequences.

In accordance with the invention, a yarn carrier or "box" having the usual yarn guide is provided with a novel cam projection. A second yarn carrier or box is also provided with a similar cam projection. Both of these carriers are movable in tandem along a stationary trackway, or the like, usually provided in a knitting machine of the type generally known as a links and links machine. It is an important feature of the invention that addition of a trackway or provision of a special trackway is not required to obtain benefits of the invention. Also, the yarn selector mechanism of the knitting machine need not be modified to cooperate with the yarn carriers or boxes, each of which is provided with the special cam of the invention, to effect selection and operation of a desired box.

Selection of the desired box is facilitated by a special trackway cam which is controlled by the cam of one of the boxes. The special trackway cam and the trackway stops guide the yarn selector finger of the carriage mounted portion of the yarn selector mechanism.

The principal object of the present invention is to provide a novel yarn carrier or box which can be employed as an additional box on the existing stationary trackway of a knitting machine without requiring modification of the trackway.

Another object of the invention is to provide a set of novel trackway appliances for the yarn carrier trackway of a knitting machine whereby to permit the trackway to accommodate more than one yarn carrier.

A further object of the invention is to provide a novel cam mechanism for obtaining selective operation of a given yarn carrier or box from a plurality of boxes.

A still further object of the invention is to provide a novel stop for installation on the trackway of a knitting machine.

Other objects and advantages of the present invention will, of course, become apparent and immediately suggest themselves to those skilled in the art to which the invention is directed from

2

a reading of the following specification in connection with the accompanying drawings, in which:

Fig. 1 is a view in elevation of the left hand end and the right hand end of a portion of the bar of a knitting machine with the appliances of this invention in place;

Fig. 2 is a sectional view on line 2—2 of Fig. 1 as viewed in the direction of the arrows;

Fig. 3 is a view in plan of the left hand end of Fig. 1;

Fig. 4 is a view in plan of the right hand end of Fig. 1;

Fig. 5 is a view in elevation of the yarn carrier or box to the left as viewed in Fig. 1;

Fig. 6 is a view in elevation of the right hand box of Fig. 1;

Figs. 7, 8 and 9 are sectional views, the sections being taken on lines 7—7, 8—8, and 9—9 respectively, of Fig. 1;

Fig. 10 is a view in perspective of the right hand end of the bar shown in Fig. 1 with the appliances in place; and

Fig. 11 is a fragmentary elevation of the left hand box positioned at the left hand end of its travel.

The yarn feeding mechanism together with the bar carried mechanism for controlling and moving it, embodying this invention, is to be employed in a knitting machine of the type, for example, known as the links and links machine which includes a needle bed or beds 7 and 8, and a carriage 10, shown fragmentarily, which reciprocates over these beds. The carriage includes a lock or cam mechanism (not shown) for actuating the needles 9 in the bed or beds in sequence to form stitches in the yarn which is fed to the needles along with and under control of the carriage. Inasmuch as knitting machines of this

general type are by now well known, the mechanism of the knitting machine has been omitted for the sake of simplicity. The knitting machine usually includes one or more trackway bars 12, four of which are indicated in Fig. 2 of the drawing.

These trackway bars are supported in any suitable manner so that they lie above the needle beds 7 and 8 of the knitting machine. In the illustrative example, only one trackway bar 12 is shown by full lines in the several figures of the drawing. The plurality of bars 12 are spaced horizontally and the yarn guides are offset laterally from their carriers to insure that yarn is fed to the needles in their active position. The trackway bar 12, as shown in Fig. 2, has two dovetail projections 14 and 16 which extend longitudinally

of the bar. Reference character 18 designates, in its entirety, one carrier or box for a yarn feeder 19 which serves yarn for a knitting operation.

The feeder 19 is supported from the box by a branch 20. The box 18 is or may be of usual construction with an exception to be noted. The branch 20 and the feeder 19 feeds a strand of yarn in known manner through a hole 21. The carriage 10 is equipped with a finger 22 which telescopes over a plunger 23. A compression spring 24 presses the finger 22 downwardly to operating position. A limit stop (not shown) sets the downward limit of movement of the finger 22. The plunger 23 has a projection 28 which is controlled by a bar member 29. The just described device is shown in detail in Patent No. 2,493,054. The box 18 is provided with an added projection 33 having a cam surface 34.

In accordance with the invention a second carrier or box 36 is provided which has a branch 38 and a feeder 39. A cam projection 42 on the box 36 presents a cam surface 43. The cam surface 34 and 43 cooperate in a special manner with a roller 46, or its equivalent, which turns a rock shaft 48 to move a cam or finger guide 51 in a manner and for a purpose to be described. The cam 51 has a sloping cam surface 52.

The carrier 36, like the carrier 18, is provided with a recess 53, the top portion of which is of a shape in outline to fit over a dovetail portion of a trackway bar such as the portion 14. A member 56 is slidably mounted on the body of the carrier 18 and it is provided with a surface which presses upwardly against the bottom of the projection 14. A flat spring 58, secured to the body of the carrier 18, presses the member 56 upwardly so that the carrier 18, while it is slidable on the projection 14, is frictionally held in position unless it is moved positively by a yarn selecting instrumentality, a part of which, namely, the finger 22, appears on the drawing.

The degree of offset of each branch, such as 20, will be determined by the placement of the trackway bar laterally with respect to the active position of the needles. The feeders are or may be beveled at their ends in the usual manner.

Considering the right hand portion of Fig. 1, the boxes 18 and 36 are in the position shown with respect to a stopper carrying device or block 62 and the cam 51 such as the box 36 will be selected for operation by the finger 22 of carriage 10 when it is lowered by the bar 29. The previously mentioned rock shaft 48 is rotatably carried by bearing brackets 66 and 67. These bearing brackets are secured to an arm 71 extending from the block 62. The block 62 is clamped in the selected position on the dovetail by a thumb screw 74. The selected position of the block 62 is shown in Fig. 1. A finger 76 having a sloping cam surface 78 is pivoted near the end of the arm 71. A flat spring 79 urges the finger 76 inwardly toward the trackway bar 12. A similar finger 81 having a sloping cam surface 83 is provided on the arm 71.

The left hand portion of Fig. 1 shows appliances similar to the cams 76 and 81 and the cam 51. Referring to the left hand side of Fig. 1, a block 84 is clamped to the rail by a set screw 86. This block is provided with an arm 88. The arm 88 carries a pivoted spring pressed cam 91 having a sloping cam surface 93. A cam 96 having a sloping cam surface 98 is also pivoted on the arm 88. A rock shaft 101 carries a cam 103 having a sloping cam surface 104. A roller 106, similar to the roller 46, is en-

gaged by the cam surface 43 or 34 in operation of the device of this invention.

The operation of the illustrative embodiment of the invention will now be described. The box 18, together with its branch 20 and feeder 19 can operate to serve yarn to the needles in the needle bed or beds. Likewise, the box 36 together with its branch carried feeder 39 is operable, when selected, to feed yarn to the needles. With the parts in the position shown at the right of Fig. 1, it will be assumed that the carriage 10 has completed its travel to the extreme right, beyond the limit of the drawing, and is returning to the left. It will also be assumed that the finger 22 is lowered to its operative position. The finger 22 encounters the sloping surface 52 of the cam 51 and is raised against the thrust of the spring 24. The finger 22 rides along the top of the box 18 without engaging its edge 116. When the finger 22 reaches the end of the top of the box 18, it drops down to engage the edge 118 of the box 36. As the carriage 10 continues to the left, it moves the box 36 by engagement of the finger 22 with the box edge 118. During this time, yarn is or may be fed to the needles. In its movement to the left, the finger 22 will push the cams 76 and 81 aside. Also, the roller 46 drops to raise the cam 51, which is not significant at this time. A tension spring 89 biases the roller 46 down and the cam 51 up.

At the end of the yarn feeding stroke toward the left, the pin 22 engages the sloping surface 93 of the finger 91 and is raised to release the edge 118 of the box 36. This position of the parts is shown in Fig. 11 of the drawing. The carriage continues its movement to the left to the end of its stroke without propelling the box 36. As the cam 103 is raised by the spring 120, movement of the pin 22 is permitted without interference.

On the carriage return stroke to the right the finger 22 passes beside the cam 103 and engages the edge 128 of the box 36 to return it to the right. The box is released when the pin 22 rides up upon engagement with the sloping surface 78. The box 36 is thus left in its original position. The cam surface 43 raises the roller and lowers the cam 51. The carriage 10 continues to the right to the end of its stroke and returns to again operate the box 36. This is continued for as long as operation of the box 36 is desired.

To select the box 18 for operation, the box 36 is moved by the carriage to the left until the finger 22 is released from engagement with the box by the cam surface 93 of the finger 91. The pin 22 of the carriage is raised and the carriage makes an idle stroke to the right. At this time, the roller 46 is down and the cam 51 is raised. When the carriage has completed its idle stroke to the right, the pin 22 is lowered. The carriage now starts to the left. Since the cam 51 is raised, the pin 22 is permitted to engage the edge 116 of the box 18. The box 18 is propelled to the left and pushes the box 36 to the extreme left. The pin 22 is released from the edge 116 of the box when the pin 22 engages the slope 93 of the cam 91.

The carriage continues to the left and upon its return to the right, the pin 22 rides up over the sloping end 104 of the cam 103, moves over the top of the box 36 and engages the edge 140 of the box 18 to propel it to the right. When the pin 22 engages the slope 78 of the finger 76 the box is released. This operation may continue as long as is desired.

To resume operation with the box 36, the box 18 is left in or near the original position of the box 36. The carriage makes an idle stroke to pick up the box 36 putting the box 18 to the extreme right.

What is claimed is:

1. A yarn feeding mechanism for a knitting machine comprising a block member having a recess therein to be received on the trackway of a knitting machine, an arm having a yarn feeder on said block, a second block having a recess to be received on the trackway of a knitting machine, an arm having a yarn feeder on said second block, cam means on each of said blocks, and means comprising a friction shoe and a spring on both said first named block and said second named block for frictionally positioning said blocks on a trackway of a knitting machine.

2. In combination in a knitting machine having a trackway for yarn feeding devices and a reciprocable carriage having a finger for engaging and propelling said devices; a pair of cams for raising said finger, each cam being beyond the selected range of travel of said devices, two pairs of pivoted finger-lifting cams, one pair being positioned adjacent each end of the range of movement of said devices, a pair of blocks constructed to be secured to said trackway, each block carrying one pair of said pivoted finger-lifting cams, each block having means to carry one of said first named cams for actuation, and each of said last named means having a cam follower, said last named cam followers being positioned for engagement with said yarn feeding devices.

3. A multiple yarn feeding mechanism for a knitting machine having a trackway for yarn feeding devices; said mechanism comprising a plurality of yarn feeding devices slidable on said trackway, a cam member beyond one limit of travel of said devices for cooperation with the yarn feeder actuating finger on the reciprocating carriage of said knitting machine, a rock shaft to which said cam is attached, means to bias said rock shaft for rotation in a direction to move said cam from a finger-engaging position, a cam follower extending from said rock shaft, and a cam on each of said yarn feeding devices, said last named cams being positioned for engagement with said cam follower as said devices reciprocate on said trackway.

4. A yarn-feeding mechanism for a knitting machine comprising a block member having a recess therein to be received on the trackway of a knitting machine, an arm having a yarn feeder on said block, a second block having a recess to be received on the trackway of a knitting machine, an arm having a yarn feeder on said second block, cam means on each of said blocks, means comprising a friction shoe and a spring on both said first-named block and said second-named block for frictionally positioning said blocks on a trackway of a knitting machine, a block and means for clamping said block to said trackway, said block having a cam follower projecting therefrom in the path of said cam means, and a cam controlled by said cam follower to be moved to a position over said trackway.

5. In combination in a knitting machine having a trackway for a yarn feeding device and a re-

ciprocable carriage having a finger for engaging and propelling said devices; a cam for raising said finger, said cam being beyond the selected range of travel of said device, a pair of pivoted finger-lifting cams, said pair being positioned adjacent the end of the range of movement of said device, a block constructed to be secured to said trackway, said block carrying said pair of said pivoted finger-lifting cams, said block having means to carry said first-named cam for actuation, and said last-named means having a cam follower, said last-named cam follower being positioned for engagement with said yarn feeding device.

15 6. A multiple yarn feeding mechanism for a knitting machine having a trackway for yarn feeding devices; said mechanism comprising a yarn feeding device slidable on said trackway, a cam member beyond one limit of travel of said device for cooperation with the yarn feeder actuating finger on the reciprocating carriage of said knitting machine, a rock shaft to which said cam is attached, means to bias said rock shaft for rotation in a direction to move said cam from a finger-engaging position, a cam follower extending from said rock shaft, and a cam on said yarn feeding device, said last named cam being positioned for engagement with said cam follower as said device reciprocates on said trackway.

20 7. A multiple yarn feeding mechanism for a knitting machine having a trackway for yarn feeding devices; said mechanism comprising a yarn feeding device slidable on said trackway, a cam member beyond one limit of travel of said device for cooperation with the yarn feeder actuating finger on the reciprocating carriage of said knitting machine, a rock shaft to which said cam is attached, a spring for biasing said rock shaft for rotation in a direction to move said cam from a finger-engaging position, a cam follower extending from said rock shaft, and a cam on said yarn feeding device, said last named cam being positioned for engagement with said cam follower as said device reciprocates on said trackway.

25 8. A multiple yarn feeding mechanism for a knitting machine having a trackway for yarn feeding devices; said mechanism comprising a yarn feeding device slidable on said trackway, a cam member beyond one limit of travel of said device for cooperation with the yarn feeder actuating finger on the reciprocating carriage of said knitting machine, a rock shaft to which said cam is attached, means to bias said rock shaft for rotation in a direction to move said cam from a finger-engaging position, a cam follower extending from said rock shaft, and a cam surface on said yarn feeding device, said cam surface being positioned for engagement with said cam follower as said device reciprocates on said trackway.
